TRAY OR SIMILAR ARTICLE

Robert L. Gruen, New York, N. Y., assignor to Continental Silver Co., Inc., a corporation of
New York

Application July 18, 1952, Serial No. 20,670

Term of patent 3½ years

(Cl. D44—10)

To all whom it may concern:

Be it known that I, Robert L. Gruen, a citizen of the United States and residing at New York, in the county of New York and State of New York, have invented a new, original, and ornamental Design for a Tray or Similar Article, of which the following is a specification; reference being had to the accompanying drawings, forming part thereof, and in which

Fig. 1 is a perspective view of a tray showing my new design,

Fig. 2 is a plan view thereof,

Fig. 3 is a front elevation thereof, and

Fig. 4 is a cross sectional view taken on line 4—4 of Fig. 1.

I claim:

The ornamental design for a tray or similar article, substantially as shown.

ROBERT L. GRUEN.
